PET TRAVEL KIT

Charles H. Holycross, 240 Eldridge St.,
Long Beach, Calif. 90807

Filed Feb. 24, 1970, Ser. No. 21,583

Term of patent 3½ years

Int. Cl. D30—01

U.S. Cl. D30—1

FIG. 1 is a front perspective view of a pet travel kit showing my new design;

FIG. 2 is an end elevation thereof, the end opposite being a mirror image;

FIG. 3 is a rear elevation thereof;

FIG. 4 is a front elevation thereof;

FIG. 5 is a front perspective view thereof in open condition; and

FIG. 6 is a fragmentary perspective view of the hinged side after removal therefrom.

I claim:

The ornamental design for a pet travel kit, as shown and described.
